Patented Feb. 9, 1915.

Fig. 1.

UNITED STATES PATENT OFFICE.

SIDNEY I. WHARTON, OF LEXINGTON, OKLAHOMA.

WINDOW-SHADE ROLLER.

1,128,204.

Specification of Letters Patent.

Patented Feb. 9, 1915.

Application filed March 12, 1914. Serial No. 824,230.

To all whom it may concern:

Be it known that I, SIDNEY I. WHARTON, citizen of the United States, residing at Lexington, in the county of Cleveland and State 5 of Oklahoma, have invented certain new and useful Improvements in Window-Shade Rollers, of which the following is a specification.

This invention relates to certain new and 10 useful improvements in shade rollers and adjustable supports therefor.

The primary object of the invention is to provide a device of the above described character, wherein the support may be adjusted to accommodate shade rollers of various lengths and to also provide, in connection with such a support, a shade roller operable by a cord to effect the raising or lowering of the shade carried by the roller, 20 thus eliminating in the roller the expensive spring construction now common upon the market.

A further object of the invention is to provide a shade roller and support therefor, 25 the roller being operable by a cord and the support carrying a resilient guide for the cord, said guide acting to maintain the cord in position operatively engaged with the roller to insure the efficient operation of the 30 device.

The invention has as a further object to provide a roller, wherein the shade may be easily and readily attached to or detached from the roller. And the invention has as a 35 still further object to generally improve the construction and increase the efficiency of devices of the above described character.

With these and other objects in view my invention will be more fully described, illustrated in the accompanying drawings, and then specifically pointed out in the claims 40 which are attached to and form a part of this application.

In the accompanying drawings: Figure 1 45 is a perspective view showing my improved shade roller and support in position upon a window casing, the window casing being conventionally shown. Fig. 2 is a fragmentary perspective view, especially showing 50 one of the shade brackets and the relative disposition of the cord guide carried thereby. Fig. 3 is a transverse sectional view, showing the pulley mounted to rotate with the shade roller, the cord being shown in position upon the pulley and the cord guide being illustrated in proper operative position.

Fig. 4 is a fragmentary longitudinal sectional view taken on the line 4-4 of Fig. 3 showing the disposition of the pulley upon the shaft carrying the shade roller. Fig. 5 60 is a fragmentary perspective view showing the manner in which the shade is secured to the shade roller, and Fig. 6 is an end view showing my improved shade roller bracket as used to support a curtain pole. 65

Corresponding and like parts are referred to in the following description and indicated in all the views of the accompanying drawings by the same reference characters.

In carrying out my invention I employ a 70 base rod 10 which may be formed of wood, or any other suitable material, and which is preferably oblong in cross section as shown. The base rod 10 may be made of any desired length, being preferably of a length to extend 75 across the average window opening, and is designed to be secured upon the outer face of the window casing above the window opening, metallic clips 11 being preferably employed to support the rod in position. 80

Mounted to slide upon the base rod 10, longitudinally thereof, are shade brackets 12 and 13, such brackets constituting a pair and adapted to support the shade roller. It will be understood that the brackets of 85 each pair are slightly different in construction and that said brackets are, of course, designed to be manufactured and sold in pairs. Each of the brackets 12 and 13 are preferably integrally formed from suitable sheet 90 metal bent upon itself to define guide loop 14 designed to embrace the base rod 10 and slide freely thereon, the free extremities of the portion of the bracket forming the loop being disposed in spaced relation, as shown 95 at 15°. Extending at right angles from one edge of each of the guide loops 14 is a bracket arm 15 which is provided with a circular aperture 16 designed to receive one 100 extremity of the shaft supporting the shade roller, the shaft being mounted to rotate in said apertures. The bracket arms 15 may be made of any desired fanciful conformation, so as to enhance the appearance of the support, but said arms are preferably formed 105 upon one edge with an upstanding inwardly curved portion 17, disposed to receive a curtain pole.

The brackets 12 and 13, as thus far described, are identical in construction, and it will be clear that said brackets may be positioned longitudinally of the base rod 10 to

conform to window openings of various widths, and so as to effect adjustment of the brackets to accommodate shade rollers of various lengths. One bracket of each pair of brackets, and in this instance, the bracket 12, is designed to carry a cord guide 18. The cord guide 18 is preferably formed from a strip of suitable resilient metal bent intermediate its ends to provide outwardly diverging arms 19 and 20, the free end of the arm 19 being curved inwardly toward the arm 20, with the extremity 21 thereof disposed at substantially right angles to the body portion of the arm and terminating in spaced relation to the extremity of the arm 20. The extremities of the arms 19 and 20 are transversely curved, as shown at 22, providing grooves adapted to receive the cord. Struck from the face of the bracket 12 is a lug 23, the metal forming said lug being bent over to engage the intermediate portion 24 of the cord guide 19, thus supporting the cord guide upon the bracket. The free extremity of the arm 20 is curved outwardly away from the free extremity of the arm 19, as at 25.

Supported by the brackets 12 and 13 is a shade roller 26 which is mounted upon a shaft 27, the extremities of which are mounted to rotate in the apertures 16 formed in the bracket arms 15. The shaft 27 may be formed of wire, the roller being bored to receive the wire, and said wire may be flattened, as shown at 28, to thus prevent rotary movement of the roller 26 independently of the shaft 27.

Mounted upon one extremity of the shaft 27 and spaced from the adjacent end of the roller 26 is a pulley 29. The pulley 29 may be secured to the shaft in any suitable manner and is preferably provided in its outer face with a substantially V-shaped groove 30, adapted to receive the cord 31 by which the roller is operated to either raise or lower the curtain 32 carried by the roller.

Particular attention is directed to the peculiar disposition of the cord guide 18, as best shown in Fig. 3 of the drawings. It will be observed that when the roller 26 is mounted upon the bracket arms 15, the arms 19 and 20 of the cord guide 18 are disposed to embrace the pulley 29. As heretofore stated, the arms 19 and 20 are formed of resilient material and are so spaced as to normally bear against the cord 31, to thus maintain the cord in the groove 30 of the pulley 29. Preferably, the roller 26 is of greater diameter than the pulley 29, the adjacent end of the roller acting to prevent displacement of the cord 31 over one edge of the pulley while the adjacent bracket arm 15 serves to prevent displacement of the cord over the opposite end of the pulley.

The curtain 32 is preferably secured to the roller 26 by the rod 33 which is held by

staples 34, the roller being grooved longitudinally, as at 35, to receive the rod. Thus the curtain may be readily attached to or detached from the roller without mutilating the curtain, the fixed extremity thereof being positioned in the groove 35 and held by the rod 33. 70

In connection with the operation of my improved support, it should be noted that the cord guide 18 serves to hold the curtain 32 in adjusted position. The resilient arms 19 and 20 of said guide bearing against the cord 31 and clamping the pulley 29 sufficiently to prevent movement of the roller carrying the curtain. Thus, the shade may 75 be positioned at any desired height with reference to the window opening. It will be noted that when the cord 31 is operated to roll up the curtain, downward pull upon the intermediate portion of the cord will 80 cause the adjacent extremity of the arm 20 of the cord guide to be sprung away from the roller, tension upon the cord causing it to bear outwardly against said arm, the extremity of the arm being grooved to present 85 a smooth bearing surface for the cord. As a consequence, the tension of the cord guide upon the pulley is partly relieved allowing it to revolve more freely. 90

My improved shade roller support may be 95 also used to support a curtain pole 36, the pole being placed upon the upper edges of the brackets 15 as best shown in Fig. 6 of the drawings. When thus used, draperies suspended from the pole 36 may be arranged 100 to extend over the shade 32, if desired, or may be allowed to hang between the shade roller supporting the shade and the rod 10. Thus, my improved support may be used to hang window curtains and where it is not 105 desired to employ a shade, the shade may, of course, be omitted.

It will therefore be seen that I provide a very simple and efficient structure for the purpose set forth, such as may be adjusted 110 to window openings of various widths, and wherein the curtain roller is operated by a cord, thus obviating a spring roller construction such being more or less expensive to manufacture. It will also be seen that I 115 provide means whereby the cord is held in positive engagement with the pulley mounted to rotate the roller carrying the curtain, and also provide a resilient guide for the intermediate portions of the cord. 120

Having thus described my invention, what I claim as new is:

1. A device of the character described including a support, brackets carried by the support, a shade roller supported for rotation by said brackets, a pulley mounted to rotate with the shade roller, a cord engaging the pulley, and a cord guide carried by one of the brackets and engaging the cord, said cord guide being formed from a single 125

strip of metal bent intermediate its ends to provide diverging resilient arms, one of said arms being laterally bent adjacent its free extremity to extend toward the pulley and each of said arms being grooved transversely at the adjacent ends thereof to bear against the cord upon opposite sides of the pulley.

2. A device of the character described including a support, brackets carried by the support, shade bracket arms formed on said brackets, a lip struck from one of said brackets and adapted to be bent over to engage a cord guide, a cord guide carried by

said lip and being formed with spaced resilient arms, a roller supported for rotation by said bracket arms, a pulley mounted to rotate with the roller and embraced by the arms of the cord guide, and a flexible element passing around the roller and engaged by the arms of the cord guide.

In testimony whereof I affix my signature in presence of two witnesses.

SIDNEY I. WHARTON. [L. s.]
